F. J. CREQUE

NURSING BOTTLE

Filed April 8, 1924

Inventor

F. J. CREQUE

By

Asst. Atty.
Attorney

UNITED STATES PATENT OFFICE.

FRANK J. CREQUE, OF CUYAHOGA FALLS, OHIO.

NURSING BOTTLE.

Application filed April 8, 1924. Serial No. 704,979.

To all whom it may concern:

Be it known that I, FRANK J. CREQUE, a citizen of the United States, residing at Cuyahoga Falls, in the county of Summit 5 and State of Ohio, have invented certain new and useful Improvements in Nursing Bottles, of which the following is a specification, reference being had therein to the accompanying drawing.

10 This invention relates to certain new and useful improvements in nursing bottles, the object being to provide a bottle which is so constructed that air will be admitted into the bottle as the milk is drawn out through 15 the nipple so as to prevent a vacuum from being formed, thereby overcoming the difficulties existing with the nursing bottles now in use.

Another and further object of the invention 20 is to provide a bottle with a vent closed by a flexible member which is so constructed that it snugly fits the neck of the bottle so as to prevent the milk from passing out through the vent yet allows air to pass in 25 through the vent into the bottle as the milk is withdrawn.

Other and further objects and advantages of the invention will be hereinafter set forth and the novel features thereof defined 30 by the appended claims.

In the drawing I have shown a side elevation of a nursing bottle, partly in section, illustrating one embodiment of my invention and while I have shown a specially shaped 35 bottle, it is, of course, understood that I do not wish to limit myself to any particular shape of bottle or the number of vents used.

40 In carrying out my invention I employ a bottle, preferably formed of glass, comprising a body 1 having a neck 2 which tapers from the shoulder of the bottle to the mouth of the neck and is provided with an interior annular groove for the purpose hereinafter fully described.

The neck of the bottle is provided with 45 an air vent 3, the outer wall of the neck being enlarged around the vent as clearly shown, but it is, of course, understood that 50 this is not essential and the outer wall of the neck might be provided with an annular rib through which the vent or vents could extend.

Arranged within the neck of the bottle is 55 a rubber sleeve 4 provided with an enlarged

upper edge 5 forming an annular bead adapted to be seated in the annular groove formed in the neck of the bottle at the mouth. The sleeve slightly tapers from the bead or upper edge towards the lower edge 60 thereof and is adapted to fit snugly within the neck of the bottle.

The sleeve is inserted from the top and as the neck gradually tapers, it fits snugly 65 the interior of the neck at the junction of the body so that the contents of the bottle is prevented from passing out around the sleeve.

The tube collapses so as to allow air to enter the vent and pass into the interior of the 70 bottle.

An ordinary nipple 6 can be used and as the milk is drawn out of the bottle through the nipple, the sleeve yields in order to allow air to pass through the vent into the 75 body of the bottle which prevents the nipple from collapsing, thereby overcoming the difficulties now existing with nursing bottles.

From the foregoing description it will be 80 seen that I have provided a nursing bottle with a neck having a vent in the wall thereof over which is arranged a rubber sleeve having an annular bead at its upper edge to reinforce the same to facilitate the insertion 85 of the sleeve within the neck, whereby a bottle is constructed which allows air to enter the same as the contents is drawn out.

The sleeve can be readily removed and the 90 bottle sterilized in the ordinary manner, the sleeve being also sterilized so that a thoroughly sanitary bottle is formed and as the vent hole is protected by the sleeve, it is never exposed to the contents of the bottle.

As the contents of the bottle is withdrawn 95 through the nipple, a partial vacuum is created within the bottle and the rubber sleeve collapses slightly so as to allow air to come in through the vent hole.

What I claim is:

1. A nursing bottle provided with a neck 100 having a vent in the wall thereof and a flexible sleeve arranged within the neck of the bottle over said vent and forming a valve for said vent.

2. A nursing bottle having a tapering neck provided with a vent and a flexible rubber sleeve arranged within said neck over said vent and forming a valve for said vent.

105

110

3. A nursing bottle having a vent and a rubber sleeve arranged over said vent to form a valve for said vent and so constructed that the contents of the bottle passes 5 through said sleeve and the valve opens to allow air to enter said bottle through said vent when a partial vacuum is created therein.

4. As a new article of manufacture, a 10 nursing bottle having a tapering neck provided with a vent in the wall thereof, a rubber sleeve arranged within the neck of said bottle extending from the mouth of the neck to a point beyond the vent and 15 forming a valve for said vent.

5. A nursing bottle having a neck provided with a vent in the wall thereof and an annular groove at the mouth, a flexible sleeve arranged within the neck of the bottle having an annular bead at its upper edge 20 seated in the annular groove of the neck, said flexible sleeve extending over the vent and fitting the interior of the neck of the bottle snugly to prevent the contents of the bottle from passing out through the vent 25 and to allow air to enter said bottle when a partial vacuum is created therein.

In testimony whereof I hereunto affix my signature.

FRANK J. CREQUE.
